DETACHABLE FEED BELT FOR AUTOMATIC FIREARMS

Niccolo Mancini, Florence, Italy

Application March 19, 1934, Serial No. 716,273
In Germany March 20, 1933

6 Claims. (Cl. 89—35)

The present invention relates to metal feed belts for automatic fire arms composed of separate elements and is intended to give a simple form to the web and to render it suitable for all uses and also for all angles of firing.

It is well known that the cartridge-webs in ordinary use may readily be rolled up in a direction parallel to the cartridge though presenting a certain rigidity in the direction of the plane of the cartridge. This interferes with the introduction of the cartridges in the case of firing with a large firing angle.

This drawback is eliminated according to the invention through the oval shape imparted to the eyelets of the hinges which hold the separate parts of the belt together. This ovalization allows of a certain play between the separate parts and thus confers upon the web considerable pliancy in a transversal direction as well.

Two examples of execution of the invention are shown in the drawings, i. e.—

Fig. 1 represents a view of the web element seen from above and from the side, and

Fig. 1a is a corresponding edge view.

Fig. 1b is a corresponding end view.

Fig. 2 shows a group of various elements seen from above and from the rear.

Fig. 2a is a corresponding end view.

Figs. 3 and 4 show a second form of execution of the invention.

Fig. 3a is a corresponding edge view.

Fig. 3b is a corresponding end view.

Fig. 4a is an end view corresponding to Fig. 4.

As apparent from Fig. 1, the belt is composed of two flat rectangular metal parts, namely, the web portion 1 and the clip portion 2 of which 1 is provided with two rims 3 and 3¹ so shaped that they are enabled to hold fast the cartridges. The clip portion 2 carries an abutment 4 arranged perpendicularly to the plane thereof, against which abutment the bottom of the cartridge rests, in order to secure it evenly to the belt.

The two parts 1 and 2 are connected together through oval hinges 5 and 5¹ in such a manner that longitudinal axis of the oval is perpendicular to the plane of the element (Fig. 1).

In Fig. 2 various elements are associated in order to show the formation of the loaded belt. The part of the web portion which carries the abutment 4 is so laid upon the part of the clip portion that carries the rims that it will lie between these rims. Thereupon, the cartridge is inserted between the rims. Thus, the cartridge holds the two elements together. In this manner, the entire web may be made up.

Hence there also ensues the function of the web. As soon as the cartridge is discharged and removed from its position in the belt, the web portion is deprived of the support of the element preceding it, so that it becomes detached from the belt through the vibrations of the gun and from the web, due to the force of gravity, as indicated in Fig. 2.

Due to the oval formation of the hinge knuckles, the plane of one part of the web element is enabled to divaricate somewhat from the plane of the adjacent one. Thus a certain possibility of torsion is ensured to the belt, whereby the introduction of the cartridges is facilitated.

Figs. 3 and 4 represent a second form of execution of the invention. Fig. 3 shows an element of the web that is composed of two parts connected together by means of hinges. Part 6 is a rectangular plate and carries the projections 7 and 7¹ that hold the cartridges, and the abutment 8 by which the cartridge is checked. The web portion 10 is hinged at 9 to the part 6. This web portion 10 carries at its free extremity a projection 11. The dimensions of the several parts are so chosen, that the web portion 10 of one element may be laid upon the part 6 of a second element, as it is enabled to pass between the openings left in the righthand projections 7—7¹. The projection 11 of the web portion thus comes into alignment with the left-hand projection 7—7¹ of the part 6.

Both the parts 6 of one element and the web portion of the other element are held by the cartridge, as the cartridge is held by the two elements (Fig. 4) in the same way as in the first form of execution.

In this form of execution, likewise, the hinge eyelets may be appropriately shaped. Instead of being ovalized, the hinges may be of some similar shape, for instance, they may be of rectangular shape with semi-circular ends at their narrow sides.

Having now particularly described and ascertained the nature of my said invention and in what manner the same is to be performed, I declare that what I claim is:

1. A feed belt for automatic fire arms comprising a plurality of detachable elements connected in a series, each of said elements comprising a web portion and a clip portion articulately interconnected, said web portion being adapted to be gripped by the clip portion of the preceding element of the feed belt.

2. A feed belt for automatic fire arms comprising a plurality of detachable elements con-

nected in a series, each of said elements comprising a web portion and a clip portion, both substantially rectangular in form, said web portion being adapted to be gripped by the clip portion of the preceding element of the feed belt.

3. A feed belt for automatic fire arms comprising a plurality of detachable elements connected in a series, each of said elements comprising a web portion and a clip portion articulately interconnected, said clip portion having means for gripping the cartridge and said web portion being adapted to overlap the clip portion of the preceding element of the belt, whereby it is held in position by the cartridge gripped by said clip portion.

4. A feed belt for automatic fire arms comprising a plurality of detachable elements connected in a series, each of said elements comprising a web portion and a clip portion articulately interconnected, said web portion being provided with an abutment adjacent one extremity thereof, and said clip portion having two oppositely disposed longitudinal rims projecting from its base and adapted to grip the cartridge, said web portion being adapted to overlap the clip portion of the preceding elements of the series, whereby it is held firmly in position by the pressure of the cartridge gripped intermediate the rims of said clip portion and the abutment of said web portion.

5. A feed belt for automatic fire arms comprising a plurality of detachable elements connected in a series, each of said elements comprising a web portion and a clip portion articulately interconnected by means of a hinge, the

knuckles of said hinge being oval in shape and having its longitudinal axis perpendicular to the plane of said elements, whereby a divarication intermittent the planes of the said web portion and said clip portion is provided, and whereby the belt is given a certain torsion about an axis parallel to the edges of the belt, said clip portion having two oppositely disposed longitudinal rims projecting from its base adapted to grip the cartridge, and said web portion having an abutment adjacent one extremity thereof and adapted to overlap the clip portion intermediate said longitudinal rims of the preceding element of the series whereby it is held firmly in position by the cartridge gripped intermediate said rims and said abutment.

6. A feed belt for automatic fire arms comprising a plurality of detachable elements connected in a series, each of said elements comprising a web portion and a clip portion, both substantially rectangular in shape and articulately interconnected, said clip portion having oppositely disposed and relatively spaced projections for gripping the cartridge, and said web portion being adapted to overlap the said clip portion intermediate said projections of the preceding elements of the series and having a projection disposed adjacent its free longitudinal edge so as to fit between the corresponding projections of said clip portion, said web portion being held firmly in position against the clip portion of the preceding element by the co-action of the cartridge gripped intermediate said projections.
